US0D1110631S

(12) United States Design Patent (10) Patent No.: US D1,110,631 S
(45) Date of Patent: * Jan. 27, 2026

(54) DIRTY CLOTHES BASKET

(71) Applicant: Yuhong Song, Shenzhen (CN)

(72) Inventor: Yuhong Song, Shenzhen (CN)

() Term: 15 Years

(21) Appl. No.: 29/948,956

(22) Filed: Jun. 24, 2024

(51) LOC (15) Cl. 07-07

(52) U.S. Cl.

USPC D32/37

(58) Field of Classification Search
